UNITED STATES PATENT OFFICE.

HENRY D. CLEMONS, OF HARTFORD, CONNECTICUT, ASSIGNOR TO THE AMERICAN WRITING MACHINE COMPANY, OF SAME PLACE.

TYPE-WRITING MACHINE.

SPECIFICATION forming part of Letters Patent No. 478,223, dated July 5, 1892.

Application filed April 1, 1892. Serial No. 427,315. (No model.)

To all whom it may concern:

Be it known that I, HENRY D. CLEMONS, a citizen of the United States, and a resident of Hartford, in the county of Hartford and State 5 of Connecticut, have invented certain new and useful Improvements in Type-Writing Machines, of which the following is a specification.

My invention relates to type-writing machines provided with wide carriages, which latter, as is well known, have a considerable longer range of travel than do the carriages of the ordinary machines. Usually the ordinary machines for use by lawers and commercial houses are provided with carriages which travel about seventy steps or spaces from right to left, while the "wide" carriages, so called, employed mostly by insurance companies, have a travel generally of one hundred 20 and twenty steps or spaces.

My invention has for its object to provide means in a wide-carriage machine for actuating the signaling mechanism, which may be set or arranged in a manner to notify the operator when approaching the end of a line.

My invention consists in the features of construction and combinations of devices herein-after more fully described, and particularly pointed out in the appended claims.

30 In the accompanying drawings, Figure 1 is a front elevation of a wide-carriage type-writing machine embodying my invention, and Fig. 2 is a perspective view of the signaling mechanism.

35 In both views the same part will be found designated by the same numeral of reference.

The machine illustrated is that commonly known as the "Caligraph," and is more fully shown in an application filed by John M. Fair- 40 field March 23, 1892, Serial No. 426,078.

1 designates the top plate or type-ring, 2 the frame-work, and 3 the platen, which, as usual, is mounted in a suitable frame-work or carriage 4, of which 5 is the front rod.

45 6 is the rear hinge and guide-rail of the carriage, and 7 the front track or way, upon which run two small anti-friction rollers 8, mounted in brackets 9, secured to the front rod of the carriage. The track or way is mounted on 50 supports 10 upon the top plate, and, as usual, is provided with a scale-bar 11, preferably gradu-

ated from "0" to "120," the graduations or divisions corresponding to the number of notches or teeth of the feed-racks, and hence the number of steps or spaces of the carriage in its movement from right to left. Upon the front rod of the paper-carriage is secured by a suitable bracket a finger or pointer 12, which depends to a position in front of the scale-bar in order to exhibit the progress of the carriage, &c. The front carriage-rod is also provided with an adjustable margin-stop 13, which is clamped to the rod by a set-screw, and which is adapted to strike against a stop 14 on the end of the track or 65 way for the purpose of governing or regulating the width of margin at the left-hand side of the sheet being written upon.

On the machine frame-work is arranged a gong 15, adapted to be sounded by a hammer 16 at the lower end of an arm 17, which at its upper end is attached to a sleeve or bearing 18, fitted loosely to swing upon a pivot-pin 19, secured to the track or way. At the left-hand end of the track or way is secured another 75 pivot-pin 20, upon which is mounted another sleeve or bearing 21, which at its under side is provided with a lug or crank 22, bearing a screw or pin 23, upon which is hooked one end of a connecting-rod 24, the opposite right-hand end of which is hooked upon a similar screw or pin 25, projecting from a lug or crank 26 on the under side of the sleeve 18.

Attached to the sleeve 21 and projecting from the top of the track or way 7 is an inclined plate 27, which is adapted to be acted upon by a trip-piece 28, pivoted in a bracket 29, adjustable longitudinally of the front carriage-rod and secured in position by a set-screw 30. When the carriage moves toward the left, the trip-piece by its contact with the inclined plate 27 operates to turn and rock the sleeve 21 and through the connecting-rod 24 turn and rock the sleeve 18 and raise the bell-hammer 16. Immediately the trip-piece 85 passes off or beyond the plate 27 the bell-hammer is permitted to drop by gravity and strike against the gong to signal the operator. In returning the carriage toward the right the trip-piece by reason of being pivoted in the 90 bracket passes over the plate 27 without affecting the bell-hammer arm.

In view of the great length of travel of the carriage the ordinary arrangement will not suffice if it be desired to obtain the signal at any point within the last twenty-five degrees 5 or divisions of the scale. It will be seen that if the plate 27 were made integral with the sleeve 18 it would not be possible to ring the bell through the trip-piece 28 after the pointer 12 has passed beyond division "95" on the 10 scale. By my invention, however, the trip-piece may be adjusted to ring the bell at the extreme limit of travel of the carriage, if desired, as well as at preceding localities.

What I claim as new, and desire to secure 15 by Letters Patent, is—

1. In a type-writing machine, the combination of a gong or bell, a pivoted bell-hammer arm, an actuating-plate pivoted to a stationary part of the machine and removed from

the bell-hammer arm, a connecting-rod joining the said plate and the said bell-hammer arm, and a bell-trip upon the paper-carriage. 20

2. In a type-writing machine, the combination, with a gong or bell, of a bell-hammer arm attached to a pivoted sleeve having a crank 25 or projection, an inclined plate attached to another pivoted sleeve, also having a crank or projection, a connecting-rod uniting said pivoted sleeves through said cranks or projections, and an adjustable bell-trip upon the 30 paper-carriage.

Signed at Hartford, in the county of Hartford and State of Connecticut, this 24th day of March, A. D. 1892.

HENRY D. CLEMONS.
